Atty.

UNITED STATES PATENT OFFICE.

GEORGE JEROME BRADBURY, OF WASHINGTON, DISTRICT OF COLUMBIA.

CUFF-LINK.

1,370,779.

Specification of Letters Patent.

Patented Mar. 8, 1921.

Application filed January 6, 1921. Serial No. 435,426.

To all whom it may concern:

Be it known that I, GEORGE J. BRADBURY, a resident of Washington, in the District of Columbia, and a citizen of the United States, 5 have invented certain new and useful Improvements in Cuff-Links, of which the following is a specification.

One object of this invention is to provide a novel construction of cuff link which will 10 effectually restrain the button head from accidental release and consequent loss, but facilitate the removal of the head from the link when necessary or desirable.

Another object of the invention is to provide a cuff link which may be easily applied 15 to a cuff and which will be light, inexpensive, and of an attractive appearance.

Other incidental objects will appear in the course of the following description and the 20 invention resides in certain novel features which will be particularly pointed out in the appended claims.

The invention is illustrated in the accompanying drawings, in which—

25 Figure 1 is a side elevation of one of the cuff links embodying my invention.

Fig. 2 is a longitudinal section of the same.

Fig. 3 is a transverse section on the line 30 3—3 of Fig. 2.

Fig. 4 is a transverse section on the line 4—4 of Fig. 2.

Fig. 5 is a detail elevation showing the 35 manner of detaching the head from the link; and

Fig. 6 is a view in section of one modified form of the link.

The link is telescopic in construction and 40 comprises a central sleeve 1 and end sleeves 2, fitting closely but slidably in the opposite ends of the central sleeve. The inner ends of the sleeves 2 are open, as clearly 45 shown in Fig. 2, but the outer ends thereof are closed by the heads 3, which project an- nularly beyond the sleeves and thereby pre- 50 sent stop shoulders 4 to limit the movement of the respective end sleeves inwardly relative to the central sleeve by contact with the adjacent end of the central sleeve as will be 55 readily understood. A coiled expansion spring 5 is housed within the sleeves with its ends against the heads 3 and tends con- stantly to hold the end sleeves apart. To 60 prevent separation of the several sleeves un- der the influence of the spring I provide 65 the combined connecting rod and button car-

rier 6, which extends axially through all the sleeves and through the heads 3, the projecting ends of the rod being formed into hooks 7, which may be engaged through the 60 eyes or shanks 8 of the buttons 9. The said eyes or shanks will be held firmly against the outer face of the heads 3, by the combined action of the spring 5 and the hooks 7 and the end sleeves, thereby prevented 65 from separating from the central sleeve. For further security, the heads 3 are each provided with a notch 10 in its edge to receive the bill 11 of the hook 7, so that the eye or shank 8 may be held in contact with 70 the head and relative rotation of the head and the rod will be prevented. This construction, moreover, permits the hook to be held in engagement with the head when the button is removed, so that separation of the 75 sleeves will be prevented under all circumstances. Diametrically opposite the notch 10, each head 3 is cut away segmentally, as at 12, and the chordal face is beveled out- wardly, as shown at 13. If the rod 6 be 80 turned so that the bill 11 of the hook 7 is presented to the surface 13, the button may be easily removed from or engaged with the hook, as will be readily understood on refer- ence to Fig. 5.

85 From the foregoing description, taken in connection with the accompanying drawings, it will be readily seen that I have pro- vided a light, easily manipulated, inex- 90 pensive and attractive device which may be easily applied to a cuff and will efficiently hold the cuff closed. In applying the fas- tener to a cuff, the button may be turned to a position parallel or substantially parallel to the axis of the link and then inserted 95 through the button hole, or the button may be removed and reengaged with the link after the end of the latter has been passed through the button hole. The readiness with which the button may be engaged with 100 or detached from the link makes feasible the provision of a plurality of buttons for use in connection with the same link so that at a small cost the user may obtain a wide va- 105 riety in his dress. In applying a button to a link, the eye or shank of the button is engaged on the hook while the latter is in the position shown in Fig. 5. After the button has been fully engaged upon the hook, the latter is rotated about the axis of 110 the link, the bill of the hook riding on the outer face of the head 3 until it reaches the

notch 10, whereupon the spring 5 will instantly expand and effect engagement of the hook in the notch. Accidental separation of the parts can not then occur, and, if it be desired to remove the button, the hook must be withdrawn from the notch and then rotated until the eye of the button may be removed past the beveled face 13.

In the modification shown in Fig. 6 instead of the end sleeves 2^a fitting slidably within the central sleeve 1^a the central sleeve is slidably mounted within the end sleeves 2^a thus giving to the link a neat and attractive appearance.

Having thus fully described my invention, what I claim as new and desire to secure by Letters Patent of the United States, is—

1. The combination of a telescopic link, a button carrier passing through said link, buttons on the ends of the button carrier, and means housed within the link to yieldingly hold the ends of the carrier against the exterior of the ends of the link.

2. The combination of a telescopic link, the ends of the link being closed and provided each with a notch, a button carrier mounted in the link and terminating in hooks exterior to the link, buttons engaged on said hooks, and means for holding each hook normally in engagement with the notch in the adjacent end of the link.

3. The combination of a telescopic link consisting of a central sleeve and end sleeves slidably mounted in the central sleeve, heads closing the outer ends of the end sleeves and presenting stop shoulders to the ends of the

central sleeve, a spring housed within the sleeves and bearing against said heads, a rod extending through the heads, and buttons carried by the ends of said rod, the spring holding the heads to the ends of the rod.

4. The combination of a link, a button carrier rotatably and slidably mounted in the link, a button engaged on the button carrier, and means whereby removal of the button will be prevented when the carrier is rotated to one position of the carrier and permitted in another position thereof.

5. The combination of a link, a head at the end of the link provided with a notch and with a beveled chordal surface at a point diametrically opposite the notch, a button carrying hook slidably and rotatably mounted in said head, a button engageable with and removable from said hook when the bill thereof is presented to said beveled chordal surface, and means for normally holding the bill of the hook in engagement with the notch in the head.

6. The combination of a telescopic link consisting of a central sleeve and end sleeves slidably mounted with relation to the central sleeve, heads closing the outer ends of the end sleeves, a spring housed within the sleeves and bearing against said heads, a rod extending through the heads and buttons carried by the ends of said rod, the spring holding the heads to the ends of the rod.

In testimony whereof I hereunto affix my signature.

GEORGE JEROME BRADBURY.
